UNITED STATES PATENT OFFICE

SAMUEL H. NORTON, OF MEADVILLE, PENNSYLVANIA, ASSIGNOR TO HOOKLESS
FASTENER COMPANY, A CORPORATION OF PENNSYLVANIA

SLIDE FASTENER

Application filed August 22, 1931. Serial No. 558,687.

My invention relates to slide fasteners, that is, that class of fastening devices having cooperating interlocking means adapted to be engaged and disengaged by movement of a slider from one end to the other of the fastener.

Slide fasteners comprising a pair of flexible stringers having small plate or block-like elements attached along the stringer edges in uniformly spaced relation, have been used for several years on numerous articles of everyday use, such as rubber overshoes, handbags, children's clothing, and luggage and have become familiar to the general public.

In many cases it has been observed that the users of articles equipped with slide fasteners will employ the slider for pulling the edges of the opening together, this being possible due to the cam structure of the slider. The cases where the slider has been used most frequently in this manner occur in rubber footwear, children's leggings, corsets, bags when filled, jackets and other clothing.

The use of slide fasteners in the manner referred to has frequently resulted in catching of the guide flanges between the fastener elements and particularly in cases where attempts are made to close the fastener under considerable stress. It has also been observed that sharp corners of the fastener elements which bear hard against the walls of the slider have often caused burrs to be thrown up on the slider flanges after considerable use under stress. Such burrs tend to wear and cut the threads of the fabric stringers on which the elements are mounted, resulting in complete fastener failures. In some cases the elements have actually been moved out of place on their fabric stringers by a strong pull on the slider after one of the slider walls or flanges was caught between the fastener elements. Furthermore, in fasteners heretofore used in any case where being closed under appreciable stress, the slider runs hard and scratchy.

The principal objects of my invention are to provide an improved slide fastener which will be exceedingly smooth in operation, particularly when being used to pull together the edges of an opening under stress, to eliminate

excessive wear and burrs on the slider walls or flanges, and to avoid catching of the slider between the elements and consequent misplacement of the elements on the stringer.

Other objects and advantages of the invention will more fully appear during the course of the following specification and claims.

The above objects are preferably accomplished by a simple change in construction of the fastener elements, particularly the surfaces of such elements which guide the slider during its movement in opening and closing the fastener. Instead of making the slider engaging or bearing surface of the elements parallel to the stringer edge, they are shaped to guide the slider flange smoothly around the ends of the elements so that the slider will not catch between the elements but be carried over them in successive order. By beveling or inclining the end surfaces of the fastener elements the slider may be moved easily and smoothly to a surprising degree even though considerable stress is being placed on the fastener.

In the accompanying drawing I have shown for purposes of illustration one embodiment which my invention may assume in practice. In this drawing:

Fig. 1 is a plan view of a portion of a slide fastener having my improvement incorporated therein;

Fig. 2 is a side view of one of the fastener elements detached from the stringer;

Fig. 3 is a plan view of the same element on its recess side;

Fig. 4 is a perspective view with parts broken away showing the interior construction of the slider; and

Fig. 5 is a fragmentary longitudinal section illustrating the manner in which my invention accomplishes the objects above set forth.

The form of fastener which I have chosen for purposes of illustrating my improvement is similar to that described and claimed in the patent to Gideon Sundback No. 1,219,881, granted March 20, 1917. The fastener comprises fastener stringers 10, 11 having enlarged or corded edges 12, 13 respectively to

which fastener elements 14 are attached. A slider 15 is actuated by a pivoted pull device 16 along the series of fastener elements 14 from one end to the other of the fastener in opening and closing. The construction and principle of operation of slide fasteners is now well-known and will not be described in detail.

The fastener elements 14 are of plate or block-like form with their wider dimension extending transversely of the plane of the fastener stringers and each element has at one end an interlocking recess 17 on one of its wider faces and a correspondingly formed projection 18 on the opposite side. The elements are brought together in fanwise relation in interlocking and the projections and recesses successively engage each other to hold the fastener securely closed. At the other end each element has a pair of spaced apart arms or jaws 19 which engage around the corded edges 12, 13 and hold the elements securely in place on their respective stringers.

The slider 15 is preferably a one-piece structure formed by suitable swaging, cutting and bending operations as disclosed in the patent to Gideon Sundback 1,661,144, although it will be understood for purposes in my invention, that almost any suitable slider may be used. The slider body comprises spaced apart parallel upper and lower plates or wings 20, 21 respectively, rigidly united by a solid triangularly shaped neck portion 22 at one end and near the center of the plates. The sides of the plates are turned inwardly to provide side walls or guide flanges 23 of which four are shown, although in some cases two flanges on only one wing might suffice. A pull attaching lug 24 is formed on the upper wing for convenient attachment of the finger pull 16. The shape of the interior channel of the slider is best shown in Fig. 5, it being noted that the channel has two diverging branches 25 at one end which merge into the single channel 26 at the other end. The upper portion 27 of each guide flange, of course, extends at the same angle as the branches 25 of the channel. It will thus be seen that the inclined parts of the slider flanges serve as a cam to pull the opposed series of fastener elements 14 together inside the slider.

When, however, the edges of the article are far apart and must be pulled together under considerable stress, each stringer will hang over the slider flanges as shown in Fig. 5 and with the conventional construction it is apparent that the ends of the slider flanges catch between the fastener elements and lock the slider against further movement. In my improved construction, however, no such action takes place because the surfaces 28 on the ends of jaws 19 are inclined at a suitable angle indicated at α in Fig. 2, to the edge

of the stringer, such inclination, of course, being in the same direction as the inclination of the diverging branches 25 of the slider channel. It has been found that an inclination of about twenty degrees is most satisfactory. The lower corners of each element are thus cut back and also preferably slightly rounded so as to avoid catching on the flanges of the slider.

It will be readily apparent that my improved construction results in smooth operation of the fastener, especially when being closed under considerable strain and the maximum closing pull which can be exerted by the slider is very considerably increased. Furthermore, the surfaces 28 taken collectively will form a smooth trackway during closing of the slider and provide much greater bearing surface than the conventional types especially along the upper portions 27 of the flanges where the greatest load is placed on the slider. Thus the tendency toward wear and burrs on the slider flanges will be greatly reduced, and failures of the fastener from cut or worn tapes next to the fastener elements will be eliminated.

While I have shown and described in this application one embodiment which my invention may assume in practice, it will be understood that this embodiment is merely for the purposes of illustration and description and that various other forms may be devised within the scope of my invention as defined in the appended claims.

What I claim as my invention is:

1. A slide fastener having cooperating series of fastener elements on opposite edges of an article to be fastened, a slider movable along said series of elements for opening and closing the fastener, guide flanges on the slider, and cooperating track surfaces on said fastener elements adapted to abut against said guide flanges, said track surfaces extending substantially more than half way across the ends of the elements and being inclined outwardly from each other in the direction of closing movement of the slider to facilitate closure of the fastener.

2. In a slide fastener, a pair of fastener stringers, cooperating series of plate-like interlocking elements attached along adjacent edges of said stringers, said elements each having a projection on one side and a recess on the opposite side, a slider movable along said elements for engaging or disengaging the same, said slider having walls adapted to embrace said elements, the surfaces of said elements which abut the side walls of the slider being cut back on the recess side of said elements for at least half the thickness of the element to prevent catching of said side walls of the slider on said elements and to permit the slider to operate smoothly when closing the fastener under stress.

3. In a slide fastener, a pair of fastener

- stringers, cooperating series of plate-like interlocking elements attached along adjacent edges of said stringers, a slider movable along said elements for engaging or disengaging the same, said slider having walls defining a Y-shaped channel with diverging branches inclined outwardly relative to the edges of the fastener stringers, said slider having side walls or guide flanges, and said elements having their end surfaces adapted to abut against said side walls, said entire end surfaces being inclined in substantially the same direction as the diverging branches of the slider channel to facilitate closure of the fastener under stress.
4. In a slide fastener, a pair of fastener stringers, cooperating series of plate-like interlocking elements attached along adjacent edges of said stringers, a slider movable along said elements for engaging or disengaging the same, said slider having walls adapted to embrace said elements, the entire end surfaces of said elements which abut the side walls of the slider being inclined outwardly from the center line of said fastener in the direction of closing movement of the slider at an angle of about twenty degrees to the center line of the fastener to facilitate closure under stress.
5. In a slide fastener, a pair of fastener stringers, cooperating series of plate-like interlocking elements attached along adjacent edges of said stringers, a slider movable along said elements for engaging or disengaging the same, said slider having walls adapted to embrace said elements, each of said elements having on one end an interlocking projection at one side and a recess on the other side, and at its other end a pair of clamping jaws adapted to engage around the edge of a stringer, said jaws on the projection side of said element being substantially longer than on the recess side of said element to facilitate closing movement of the slider.
6. In a slide fastener, an interlocking element of plate-like form having at one end an interlocking projection on one face and a correspondingly shaped recess on the opposite face, and at its other end, a pair of spaced-apart clamping jaws, the entire end surfaces of said jaws being substantially inclined outwardly toward the projection side of said element so that said jaws are longer on the projection side than on the recess side of the element.

In testimony whereof I affix my signature.
SAMUEL H. NORTON.
